UNITED STATES PATENT OFFICE.

JOHN JACOBSON, OF NEW YORK, N. Y., ASSIGNOR TO WEAVE-PRINT COMPANY, A CORPORATION OF NEW YORK.

PROCESS OF PRODUCING PRINTING-PLATES.

No. 926,121.

Specification of Letters Patent.

Patented June 29, 1909.

Application filed May 18, 1908. Serial No. 433,475.

To all whom it may concern:

Be it known that I, JOHN JACOBSON, a citizen of the United States, residing in New York, in the county of New York and State 5 of New York, have invented an Improvement in Processes of Producing Printing-Plates, of which the following description, in connection with the accompanying drawings, is a specification, like letters on the drawings 10 representing like parts.

The present invention relates to a process of producing printing plates and is embodied in an inexpensive process of producing from a single design a number of plates, each of 15 which is adapted to print a portion of the design, so that by successive impressions from the several plates a color effect can be produced.

In accordance with the invention, a number 20 of transparent patterns are first produced, these patterns having surfaces provided with a large number of small and regularly spaced depressions which will hold an ink or pigment. The patterns properly 25 registered with relation to the design are successively placed over the design, and that part of the design which is to be reproduced on a single plate may be rapidly traced with a brush, the small depressions confining and 30 locating the pigment, so that the process can be rapidly carried out without exercising great care in following the outline to be traced. These transparent patterns may 35 be made by a photographic process, the swelled gelatin process being preferably employed, a plate being produced in accordance with this process from a ruled line surface similar in appearance to a half tone screen. By exposing the sensitized gelatin plate to a 40 positive made from such a screen, the spaces between the lines will be oxidized, so that when the gelatin is soaked in water the lines will swell, thus producing the regular depressions above described.

Figure 1 is a plan view of a transparent pattern of the kind used in carrying out the invention; and Figs. 2 and 3 are views of the pattern placed over a design which is to be reproduced.

Assuming, for example, that the design indicated by the reference letter A is to be reproduced in two different colors, the portion a of one color and the portion b of

another, it is necessary to make two printing plates, the printing surface of each corresponding to the particular part of the design which is to be reproduced therefrom. In accordance with this invention, one of the patterns B is first placed over the design and where the portion a of the design shows 60 through the operator rapidly brushes some opaque pigment which will settle in the depressions and will not tend to flow over the surface of the pattern. Another pattern is then placed over the design properly registered with the first, and the part over the portion of the design indicated by the reference letter b is traced as indicated in Fig. 3. These two plates can then be used in connection with any photographic process to make 70 printing plates, each of which has a certain portion conforming to a certain portion of the design for color printing by successive impressions. The use of the swelled gelatin pattern assists in carrying out the process, 75 as the non-oxidized raised portions of the gelatin surface are not adhered to by the pigment which remains in the depressions and does not tend to flow beyond the same. Furthermore, the printing plates made from 80 the patterns have a printing surface which, when reproduced, is in imitation of a woven fabric, owing to the fact that the actual outline of the design, instead of being an exact reproduction of the original design, is slightly 85 irregular, owing to the fact that the entire body of the design is made up of minute squares.

Claim.

The herein described process of obtaining 90 printing surfaces which consists in making transparent patterns having surfaces provided with regularly spaced square depressions; placing said patterns over the design to be reproduced; tracing with pigment that 95 part of the design which is to be reproduced on a printing surface; and photographically producing the printing surface from the pattern thus traced.

In testimony whereof, I have signed my 100 name to this specification in the presence of two subscribing witnesses.

JOHN JACOBSON.
